UNITED STATES PATENT OFFICE.

LOUIS TRONCHON, OF PARIS, FRANCE, ASSIGNOR TO COMPAGNIE GENERALE RADIO-TELEGRAPHIQUE, OF PARIS, FRANCE.

WIRELESS TELEGRAPHY.

1,139,821.

Specification of Letters Patent. Patented Feb. 23, 1915.

Application filed December 6, 1912. Serial No. 735,829.

To all whom it may concern:

Be it known that I, LOUIS TRONCHON, of 63 Boulevard Haussmann, Paris, France, have invented certain new and useful Improvements in and Relating to Wireless Telegraphy, of which the following is a full specification.

This invention relates to improvements in wireless telegraphy and has for its object the taking advantage of certain known results in the distribution of alternating currents for enabling the provision in the same instrumentalities of two receptions one with loose coupling and the other with tight coupling.

With this and further objects in view as will hereinafter in part be stated and in part become apparent, the invention comprises certain novel constructions, combinations and arrangements of parts as will be hereinafter specified and claimed.

In the accompanying drawing: Figure 1 is an illustrative diagram. Fig. 2 is a diagrammatic view of a set of wireless telegraphy receiving instruments.

Referring to the drawing by reference characters, and particularly to Fig. 1, an alternating current circuit A, B, is provided and divided into two branches, one consisting of B, C and D, thus including the condenser C, and the other of B, S and D including the induction coil S. As is known in the art, when C and S are varied so that the circuit B, C, D, S, B is tuned with the alternating current, the intensity of said current becomes zero in line A, B, if the ohmic resistances of the circuits B, C, D and B, S, D are sufficiently small to be considered negligible. But the ohmic resistance of these parts in actual practice are not infinitesimal and in consequence the closed circuit B, C, D, S, B presents to the passage of alternating current a very high resistance in lieu of an infinite resistance. This action of an alternating current is known, and has been used as applied in wireless telegraphy to decrease, at the reception, the effect of eddy-currents (from Stone, Jeance and Colin, etc., for the filtration of the waves). It is possible to apply this property of alternating currents in a very advantageous and quite different manner as will be later specified.

Referring to Fig. 2 of the drawing A indicates an antenna, D the self induction coil of the antenna which may be variable or not,

E a variable self induction coil, F and C variable condensers; H a ground; S a self induction coil which may be variable or not, L the detector, M a fixed condenser, T the telephone and N a two-way switch. With this arrangement of elements it is possible to secure two receptions, one with loose coupling and the other with tight coupling. The antenna circuit consists of A, R, D, B, E, F, H and may be tuned to receive either by means 60 of self induction coil D or by the condenser F.

The secondary circuit of the reception with loose coupling consists of B, K, C, Q, S, E, B and is coupled with the antenna directly by B, E.

The detector circuit consists either of B, L, M, N, P, Q, S, E, B or of B, L, M, N, O, R, D, B. Closing the switch N to contact point O affords the position of parts necessary for the reception with tight coupling or bus reception prepared to receive signals of all kinds without regulation, though susceptible of being regulated after warning, whereby a maximum number of collections 75 may be obtained and superfluous signals eliminated. The advantage of this mounting resides in the fact that it is possible to prepare the reception with loose couplings when on the bus reception and in fact the 80 switch N, being in the position N, O, and the antenna having been tuned with the transmitting station, if the capacity of condenser C or the self induction coil or both is varied in order to give to circuit B, K, C, Q, S, E 85 approximately the same frequency as that of the oscillations to which the antenna is tuned, the current will be cut off in the antenna. The result will be the same as if the antenna was untuned, and almost no sound 90 will be perceived in the telephone. Thus, in practice, when the position of the condenser C, in which no sound is received or distributed to the telephone, has been determined, the tuning of the secondary circuit with the 95 antenna will be realized and it will only be necessary to place the switch N in the position N, P, to be in the exact conditions required for the reception with loose coupling. Another advantage of the structure, as seen 100 in Fig. 2, resides in the fact that it is possible to choose in advance the degree of coupling of the antenna with the secondary circuit, according to the tuning degree desired. Moreover, this mounting also allows for the 105 110

complete elimination of neighboring stations which, because of working at short distances, are particularly inconvenient when it is desired to receive communications from a distant station. In fact, it is only necessary to have a secondary circuit for each nearby station or stations to be eliminated and to have each of said circuits tuned to its corresponding station and coupled with the coil E of the antenna.

Having thus described my invention, what I claim as new is:

The process of eliminating the effects of several disturbing stations at a radio-telegraphic receiving station and of simultaneously adjusting the receiver for efficient reception which consists in listening in over a tight coupling so as to detect all frequencies

received, simultaneously offering to the passage of the currents the large resistance produced by a slightly damped circuit loosely coupled to the receiving circuit and tuned to the frequency of the waves which it is desired to receive by adjusting such circuit until the energy of the desired frequency which reaches the telephone over the tight coupling becomes a minimum, and then listening in over the loose coupling.

In testimony whereof I have signed my name to this specification, in the presence of two subscribing witnesses.

LOUIS TRONCHON.
